UNITED STATES PATENT OFFICE.

ROSCOE CLYDE WELTY, OF OMAHA, NEBRASKA.

SIGNALING APPARATUS FOR TELEPHONE SYSTEMS.

942,763.

Specification of Letters Patent.

Patented Dec. 7, 1909.

Application filed June 2, 1908. Serial No. 436,262.

To all whom it may concern:

Be it known that I, ROSCOE CLYDE WELTY, a citizen of the United States, residing at Omaha, in the county of Douglas and State 5 of Nebraska, have invented new and useful Improvements in Signaling Apparatus for Telephone Systems, of which the following is a specification.

This invention relates to ringing apparatus for party line telephone systems and relates more particularly to a system in which the selective signaling method is employed, whereby the various bells are operated by currents in different directions or of 15 different polarities.

The invention has for one of its objects to improve and simplify the construction and operation of apparatus of this character so as to be comparatively easy and inexpensive to install and maintain in repair, and thoroughly reliable and efficient in use.

Another object of the invention is the provision of a four party line in which bias polarized ringers of the same construction 25 are employed, and in combination with which are condensers connected in series with the windings of the ringers whereby the latter may be operated by either the current charging condensers or the current 30 incident to the discharge of the condensers, the windings of the ringers being so disposed that the magnetic fluxes will be such that only one ringer will respond to a particular current or combination of currents.

35 A further object is the employment of a novel form of ringing machine including commutator, collector and discharge rings for producing the various circuits to actuate the individual ringers, and more particularly to actuate one ringer by positive currents flowing over both line wires simultaneously, the second ringer by negative currents passing over both line wires simultaneously, the third ringer by a positive current 40 over one wire and a negative current over the second wire, and the fourth ringer by a negative current over the first line wire and a positive current over the second line wire simultaneously.

50 With these objects in view and others, as will appear as the description proceeds, the invention comprises the various novel features of construction and arrangement of parts which will be more fully described hereinafter and set forth with particularity in the claims appended hereto.

In the accompanying drawings, which illustrate certain embodiments of the invention, Figure 1 is a diagrammatic view of a four party line ringing circuit having a 60 ringing machine whereby the ringers are actuated by charging currents. Fig. 1^a is a section on line *a*—*a*, Fig. 1. Fig. 2 is a similar view showing a modified form of ringing machine whereby the currents incident to the discharge of the condensers is employed for actuating the ringers or bells. Figs. 3 to 6 illustrate modified forms of ringing machines of the condenser discharging type. Fig. 7 is a modified form of ringing machine of the condenser charging type. 65

Similar reference characters are employed to designate corresponding parts throughout the several views.

Two methods are employed for ringing 75 the bells, and according to the first, any particular bell is actuated by current passing simultaneously through both windings thereof during the charging of the condensers, and in the second method the ringing of any 80 particular bell is produced by currents incident or accompanying the discharge of the condensers. The polarized ringers are so designed and the windings so connected in circuit that current flowing through one 85 winding at a time will have no ringing effect. Hence, under the first method there are three successive currents necessary for each actuation of the armature of a ringer: first, the simultaneous currents passing through each 90 and every ringer; second, current passing through one winding of each ringer or bell from one condenser; and third, the current flowing through the second winding of each ringer from the other condenser; whereas, 95 under the discharging method, the corresponding condensers of each and every ringer are charged by the first current, the other condensers by the second current, and both condensers of each and every ringer 100 simultaneously discharged for operating that particular ringer in which the magnetic flux is proper for ringing the bells.

Referring to the drawings, A, A¹, A², A³, are the ringers or bells of a four selective 105 signaling system, these ringers being of the polarized bias armature type. Each ringer comprises cores 1 and 2 that are connected together at their ends to form a closed magnetic circuit, and on the ends are pole pieces 110 3 and 4 that may be, respectively, positive and negative or vice versa, according to the

arrangement of the windings and the direction of flow of current therethrough. Presented to the pole pieces are the opposite ends of an armature 5 that carries a tapper or hammer 6 in the usual manner that is 5 adapted to strike the gongs 7, there being the usual permanent magnet 8 for polarizing the cores and armature. The windings of the electro-magnets of each ringer and of one ringer with respect to another bear definite 10 relations to each other so that currents can be passed simultaneously through all the ringers with a response in only one. The windings w , w' of ringer A are reversely wound as are also the windings of 15 the ringer A^1 , but it is to be noted that the corresponding windings of both such ringers are reversed; that is to say, the winding w of ringer A is reversely arranged with respect to the winding w of ringer A^1 , this being 20 also true of the windings w' . The windings w , w' , of ringer A^2 are wound similarly as are also the windings of the ringer A^3 but the windings of the latter are reversed with respect to those of the ringer A^2 . By 25 this arrangement, only one ringer will become operative by currents flowing in a certain direction or of certain polarity. For instance, when the currents are such as to cause the ringer A to operate, the fluxes in 30 the cores 1 and 2 of such ringer will buck each other and give the proper polarity to the pole pieces. The same currents in the windings of the ringer A^1 produce bucking 35 magnetisms in the cores thereof in such a direction as to render the pole pieces of improper polarity, while the currents passing through the windings of ringers A^2 and A^3 will be in such directions as to cause the fluxes to pass continuously through the cores 40 of the respective ringers without producing any perceptible polarity in the pole pieces. The corresponding terminals of the windings w , w' of each ringer are connected at a common point 9 that is connected to the ground 10 by the wire 11, and the other terminals of the said windings are connected, 45 respectively, with the line wires l , l' in which are arranged condensers C, C', respectively. 50 At the main station or exchange is a ringing machine R which comprises an induction or other motor M that has mounted on its shaft 12 a suitable arrangement of collector, discharge and commutator rings for establishing various circuits for actuating any desired ringer. In Fig. 1, the ringing machine is designed to cause the ringers to coöperate by current utilized in charging 55 the condensers, and continuous current is employed which, by means of the commutators, is converted into pulsating currents. 60 For this purpose, the ringing machine R comprises a pair of collector rings c , c' , discharge rings d , d^1 , d^2 , and commutator

rings k — k^5 . The collector ring c is connected with the positive side of a negative grounded battery B and the collector ring c' is connected with the negative side of a positive grounded battery B' . The commutator rings are connected to the line wires L , L' , by means of keys a , a^1 , a^2 , a^3 , that respectively control a pair of wires 13, 14, which bridge the line wires and lead to the commutator rings. These commutator rings are provided with metal commutator bars 15 with segments of insulation 16 between them and, in the present instance, six commutator rings are employed, the ring k being connected with the key a^3 , the ring k^1 with the key a^2 , 70 rings k^2 , k^3 with the key a^1 , and the rings k^4 , k^5 with the key a . The metal parts of the commutator rings are connected with the collector rings c , c' , by wires 17 and 80 18. The positive collector ring c is connected by the wire 17 with the rings k , k^2 and k^5 , while the negative collector ring c' is connected by the wire 18 to the rings k^1 , k^3 , k^4 . The wires 13 and 14 are connected with their appropriate commutator rings by 85 brushes 19, and it is to be noted that the metal parts or commutator bars 15 of these rings are so arranged that any pair of brushes will make contact with the commutator bars so as to complete the circuits 90 simultaneously, thus charging the condensers at one time. The discharge or grounding ring d is similar to the collector rings and is grounded by a wire 20 that is connected with the brush 21 which 95 constantly contacts with the grounding ring d . The other discharge rings d^1 , d^2 , are constructed like the commutator rings except that the metal parts of commutator bars 22 are so arranged that those on one ring will 100 be in advance of the corresponding ones of the other ring. The metal parts of these rings d^1 , d^2 , are connected by a wire 23 with the grounding ring d . Bridging each pair 105 of key wires 13 and 14 are the grounding wires 24 and 25 which, by means of brushes 26 and 27, are adapted to connect, respectively, with the discharge rings d^1 , d^2 . It will be understood that the various rings 110 will be insulated from each other and from the shaft, as for instance, by means of a bushing 28 surrounding the shaft at each ring, Fig. 1^a.

Normally, the keys or jacks a — a^3 are open and when it is desired to signal any particular subscriber on the party line, it is merely necessary to plug in or close the key controlling the ringer or bells of such subscriber. For instance, suppose it is desired 120 to ring subscriber A. To do this, the key or switch a is closed as shown in Fig. 1 by the insertion of a plug or equivalent means. It will be observed that the brushes 19 of the commutator rings k^4 , k^5 , are out of contact 125 with the commutator bars, and as soon as 130

the nearest bars reach the brushes by the rotation of the motor shaft 12, current will flow simultaneously through both line wires, the current being supplied by both batteries 5 B, B'. That is to say, current flows through the path consisting of the batteries B', B, in series, collector ring c, wire 17, commutator ring h⁵, wire 13 of key or jack a, line wire L', wires l' of all the ringers, each and 10 every condenser C', winding w' of the ringers, windings w, condensers C, wires l, line wire L, wire 14 of key a, commutator ring h⁴, wire 18, and batteries. The direction of flow of current is indicated by the arrows 15 designated 1, and it will be noted that the current is positive on one side of the line and negative on the other. The condensers are thus charged and the flow of current, for this purpose, will produce by the windings 20 of the ringer A, a buckling magnetic flux in the cores which develop the proper polarity for actuating the armature 5 of the ringer A. There will also be a bucking flux in the ringer A¹, but the polarity will be re- 25 verse to that in ringer A, so that the armature thereof will not be actuated. The flow of the fluxes in the magnetic circuits of the ringers A², A³, will be such that the pole pieces will be neutral. The brushes are in 30 contact with the metal parts of the commutator rings h⁴, h⁵ but for an instant, and as the motor shaft revolves, the brushes 26, 27, are successively brought into contact with the metal parts of the discharging rings d¹, 35 d², so that the corresponding condensers of all the ringers will be connected to ground at one instant and the other corresponding condensers connected with ground at another instant, thus discharging the condensers in 40 time to permit them to be immediately recharged by the brushes 19 coming into contact with the next commutator bars of the rings h⁴, h⁵. This simultaneous charging and successive discharging of the condensers 45 takes place in rapid succession, so that there will be an effective ringing of the bell A.

When the subscriber at the ringer A¹ is to be signaled, the plug or jack a¹ is inserted so that currents will pass through the line 50 wires and ringer wires in reverse direction, as indicated by the arrows designated 2, thus causing the polarity in the electromagnets of the ringers A, A¹, to be reversed so that the latter will be active and the 55 former inactive. The electro magnets of the ringers A², A³, will still be neutral, but the magnetic fluxes in each will be reversed.

When the jack a² is connected in circuit for the purpose of signaling to the subscriber at A², current will flow from the battery B' through a path consisting of the wire 30 connected with the positive side of such battery, the ground wires 11 of the ringers, both windings of the latter, condensers C, C', wires l, l', L, L', wires 13,

14 of the key a², commutator ring h¹, wire 18, collector ring c', and battery B', the direction of flow being indicated by the arrows designated 3. This flow of current which charges the condensers will produce 70 neutral fluxes in the cores of ringers A, A¹, and bucking fluxes in the cores of ringers A², A³, the flux in the former being in proper direction to develop the required 75 polarity for operating the armature and sounding the gongs. The condensers are successively discharged by means of the discharging rings so that the condensers will be in condition for receiving the next successive charging current. By thus suc- 80 cessively simultaneously charging and separately discharging the condensers, the ringer A² will be sounded as long as the key a² is closed. When the key a³ is closed, the charging current will flow from the battery B 85 through wire 17, commutator ring h, wires 13 and 14 of key a³, line wires L, L', all the wires l, l', condensers C, C' connected therewith, both windings of each and every ringer, ground wires 11, and by way of the 90 ground to the negative side of battery B. This charging current will flow in the proper direction to operate the ringer A³, while the others will be idle. The condensers are successively discharged, as before, by connecting them separately to ground through 95 the agency of the discharge rings d, d¹, d². It will thus be seen that any desired subscriber can be signaled without operating the ringers at the other subscribers' stations. 100 If desired, the principle can be carried out in connection with eight, twelve or sixteen party line systems, it being merely necessary to tune the polarized armatures of the ringers of each set of four machines and by 105 adding additional ringing machines at the central exchange for each additional four subscribers, each ringing machine generating a current of given frequency.

Referring now to Fig. 2, the system operating by simultaneously discharging the condensers for actuating the ringers will be described. The ringers and their connection with the line wires are the same as illustrated in Fig. 1, the sole difference being in the 110 construction of the ringing machine R. The induction or other motor M has upon its shaft 12 two groups of rings r and r', one group serving to connect the ringers or bells in circuit to actuate two such bells, and the 115 other group for connecting the bells in circuit for actuating the remaining two bells. The group r consists of a grounded dis- 120 charge ring 30, collector rings 31, 32, commutator rings 33, 34, 35, 36, and a dis- 125 charging ring 37 common to all the commutator rings. The wires 13, 14 of the key a² are connected with the rings 35, 36, and the corresponding wires of the key a³ are connected with the commutator rings 33, 130

34, and these two sets of wires are bridged by wires 38 and 39 to the common discharge ring 37. The discharge ring 37 is connected by a wire 40 with the grounded ring 30 and the collector rings 31, 32, are connected respectively, by wires 41, 42, to the positive and negative sides of the batteries b , b' , that are each grounded by wires 43, 44. The collector ring 31 is connected by a wire 45 with commutator rings 33, 34, while the connector ring 32 is connected by wire 46 with commutator rings 35, 36. The group r' consists of two collector rings 47, 48, commutator rings 49, 50, 51, 52, and a discharge ring 53 for connecting both sides of circuits in discharging the condenser simultaneously when operating either of two of the ringers or bells. The collector rings 47 and 48 are connected, respectively, by wires 54, 55, with the positive and negative sides of batteries b^2 , b^3 , that have their opposite sides grounded by wires 56, 57. The collector ring 47 is connected by wires 58, 59, with commutator rings 49, 52, respectively, while the collector ring 48 is connected by wires 60, 61, with the commutator rings 50, 51. The wires 13, 14, of the key a are adapted to connect with the commutator rings 49, 50, and the corresponding wires of key a' are adapted to connect with the commutator rings 50, 51, and these two sets of wires are connected by bridging wires 62, 63, with the ring 53. It will be noted that the metal segments or bars of the commutator rings for each key are arranged one in advance of another so that the two sets of condensers will be charged successively, so that the charging currents will not cause the ringers to operate.

40 In practice, the key for any desired subscriber is closed so as to thereby create a succession of three currents, namely, the currents for charging one set of condensers, the current for charging the other set, and the current resulting from connecting both sides of the circuit together to permit the condensers to simultaneously discharge for those ringing the desired bell. For instance, when the key a is closed, current flows from battery b^2 , wire 54, collector ring 47, wire 58, commutator 49, wire 13 of key a , line wire L' , wires l' , condensers C' of the ringers, windings w' of the latter, wires 11, ground, battery b^2 . As the motor shaft revolves, the other side of the circuit is completed by the ring 50 coming into contact with the brush connected with the wire 14, and current passes from the battery b^3 through the wire 57, ground, wires 11 of the ringers, windings w , condensers C , wire l , line wire L , key wire 14, commutator 50, wire 60, collector ring 48, wire 55, battery b^3 . By this current, the second set of condensers are charged. By the further rotary movement of the motor shaft, one of the metal

parts or segments of the ring 53 comes into play and the opposite sides of the circuits will be connected so as to permit the condensers to discharge and produce a current which is utilized for operating the ringer A . 70 When the key a^1 is closed, the flow of current for separately charging the condensers of the ringers will be in the opposite direction from the flow of current when the key a was closed, and also when the condensers 75 discharge the flow of current will be reversed so that the ringer A^1 will be operated. To signal the subscriber at ringer A^2 , the key a^2 is closed, thus charging one set of condensers of the ringers by current flowing from the battery b^1 , wire 44, ground, wires 11, windings w , condensers C , wires l , line wire L , wire 14 of key a^2 , commutator ring 35, wire 46, connecting ring 32, wire 42, and battery b^2 . The other set of condensers is immediately charged when the commutator 36 comes into contact with the brush of the wire 13 connected with key a^2 . Current then flows from the battery b , 80 through wire 42, collector ring 32, wire 46, commutator ring 36, wire 13, line wire L' , ringer wires l' , windings w' of the ringers, ground wires 11, ground, and battery b . Both sets of condensers are thus charged, and as soon as the opposite sides of the circuit are connected by wires 38, 39, with the discharging ring 37, the condensers will be grounded by wires 40, ring 30, and grounded wire 64. By repetition of these sets of currents, the ringer A^2 will be actuated. 85 Upon closing the key a^3 , the same circuits described in connection with the operation of ringer A^2 will be closed and opened in regular order, but in such a manner as to produce a reverse flow of current for the 90 purpose of actuating ringer A^3 as will be readily understood. 95

The ringing machine in Fig. 1 is of the eleven ring charging type and that in Fig. 2 is of the fifteen ring discharging type. 100 Referring now to Fig. 3, a twelve ring machine is illustrated that is adapted for use in operating the bells on the party line by discharge of the condensers. The several pairs of wires 13, 14, are connected, respectively, with separate pairs of commutator rings 65, 65^a, 65^b, 65^c, and the metal segments or bars of the rings of each pair are staggered or arranged one in advance of another, so that the charging circuits will be 105 completed successively. All the wires leading to the keys are connected to common bridging wires 66 that are provided with brushes 67 bearing on a common discharge ring 68, which ring is connected by a wire 115 69 with a grounded discharging ring 70. The current for charging the condensers is derived from batteries 71 arranged in the same manner shown in Fig. 1, and connected respectively with collector rings 72, 73. The 120 125 130

ring 72 is connected by wire 74 with both commutator rings 65, and one ring of each pair 65^b, 65^c, while the other collector ring 73 is connected by wire 75 with both commutator rings 65^a and the other rings of the pairs 65^b, 65^c. In Fig. 4, a thirteen ring or disk ringing machine is disclosed for actuating the bells by discharging of the condensers. This machine is composed of a ground-
ed discharging disk 76, and collector rings or disks 77, 78. The ringing keys each have a pair of commutator rings 79, 79^a, 79^b, 79^c, the first two being connected by wire 80 to collector ring 77 and the second two by the wire 81 to the collector ring 78. The collector ring 77 is also connected by a wire 82 with one ring of each pair 79^b, 79^c, and the collector ring 78 is connected by wire 83 with the other rings of the two pairs 79^b, 79^c. Two discharge rings 84, 85, are connected with the grounding discharging ring 76 by wire 86, and the ring 84 is connected by wires 87, 88, with the wires 13 of two of the keys, while the discharging ring 85 is connected by wires 89, 90, with the wires 13, 14, of the other two keys.

Fig. 5 is a ringing machine in which sixteen rings or disks are employed, the commutators and the discharging disks being so arranged as to cause the successive charging of both sets of condensers of the ringers or bells and the simultaneous discharge of the condensers. There are two collector rings 91, 92, that are connected with batteries in the same manner previously described and there are two groups 93, 94, of three rings or disks and two groups 95, 96, of four rings each. Two rings of each group are connected with the wires 13, 14, of the various keys or jacks and the wires 13, 14, of the groups 93, 94, are each connected with a discharge ring 97, the discharge rings being connected, respectively, with the collector rings 91, 92, the other rings of the group being commutator disks. Of the groups 95, 96, the rings 98, 99, are discharge rings and are connected with the wires 13, 14, controlling the other two ringers or bells and the remaining two rings of each group are connected with the collector rings 91, 92.

Fig. 6 is a ringing machine similar to that shown in Fig. 5 except that an extra pair of collector rings 100, 101, are employed which are connected in circuit during the discharging of the condensers for ringing two of the bells so as to connect in a battery b⁴ for the purpose of adding to the strength of the current incident to the discharge of the condensers, this arrangement being especially useful in long line systems. It will be noted that these collector rings 100, 101, are connected with the discharge rings of the groups 95, 96. When the discharge from

the condensers takes place by the discharge 65 rings of groups 93, 94, one or the other of the batteries 71 will be in circuit so that it will intensify the current at the time of discharge of the condensers. Referring now to Fig. 7, it will be observed that the ringing 70 machine is of the charging type like that shown in Fig. 1, except that it is equipped with a battery b⁵ that is connected with collector rings 102, 103, that are in turn connected with the commutator rings k², k³, 75 k⁴, k⁵, for supplying current to ring two of the bells, while the current to ring the other bells is derived from the batteries B, B'.

With a signaling system of this character, reliable and efficient service is rendered and 80 it does away with the necessity of relays and of having tuned armatures, and furthermore, each bell is identical in construction. It is also to be observed that a four, eight, twelve, or sixteen party line can be constructed, it being necessary merely to tune 85 the armature of each group of four subscribers having ringing machines of different frequencies.

From the foregoing description, taken in 90 connection with the accompanying drawings, the advantages of the construction and of the method of operation will be readily apparent to those skilled in the art to which the invention appertains, and while I have 95 described the principle of operation of the invention, together with the apparatus which I now consider to be the best embodiment thereof, I desire to have it understood that the apparatus shown is merely illustrative, and that such changes may be made 100 when desired, as are within the scope of the claims appended hereto.

Having thus described the invention, what I claim is:—

1. In a party-line telephone system, a ringer 105 consisting of separate cores connected together to form a closed magnetic circuit, pole pieces connected with the cores, a biased armature disposed in coöperative relation with the pole pieces, windings on the cores, means for connecting windings together at one end and to ground, lead wires connected with the opposite ends of the windings, and condensers disposed in series with the lead 110 wires.

2. In a telephone signaling system, the combination of a plurality of ringers each having separate windings and responsive to current passing simultaneously through both 115 windings in a given direction, and a ringing machine for producing current through the corresponding windings simultaneously, and another current through the other windings, and a current simultaneously through the 120 windings of each and every ringer in a given direction for operating only one of the latter.

3. In a telephone signaling system, the

combination of a plurality of polarized ringers having biased armatures and each having its windings different than those of the remaining ringers whereby each ringer responds to a predetermined set of currents, condensers connected in series one for each of said windings, means for grounding the windings, a ringing machine for connecting all the ringers in circuit, and keys for controlling the sets of current produced by the ringing machine, said ringing machine comprising a plurality of commutators, brushes bearing on the same for producing intermittent current in the ringing circuits, and grounded batteries connected with the commutators.

4. In a telephone signaling system, the combination of a plurality of polarized ringers having biased armatures and each having its windings different than those of the remaining ringers whereby each ringer responds to a predetermined set of currents, condensers connected in series one for each of said windings, means for grounding the windings, a ringer machine including separate means for producing a given set of currents, and keys or switches for connecting any current-producing means in circuit to actuate a predetermined ringer, said ringing machine comprising a rotary shaft, means for driving the same, commutators mounted on the shaft and insulated from each other, brushes bearing on the commutators for connecting the ringers in circuit, collector rings mounted on the shaft, connections between the said rings and commutators, grounded batteries, electrical connections between the batteries and collector rings, and means for effecting the discharge of the condensers.

40 5. In a ringing machine for a selective signaling party line telephone system, the combination of a plurality of commutator elements, collector rings electrically connected with the elements in a certain order, means for connecting a given element or elements in the telephone circuit, means for rotating the elements and rings together, oppositely-disposed batteries connected respectively with the collector rings and connected with the ground, and discharge rings rotating with

the other rings and periodically connected in circuit.

6. In a telephone signaling system, a ringing machine comprising a motor and its shaft, commutator rings mounted on the shaft, collector rings mounted on the shaft, a battery having its positive side connected with one of the collector rings and its negative side grounded, another battery having its negative side connected with the other collector ring and its positive side grounded, means for electrically connecting one of the collector rings with certain of the commutator rings, means for electrically connecting the other collector ring with the remaining commutator ring, wires for connecting any given commutator ring or rings in the telephone circuit, and means for periodically grounding those wires connected with the commutator rings and telephone system.

7. In a ringing machine for selective signaling party line telephone systems, the combination of a plurality of commutator rings arranged to rotate together, collector rings, oppositely-disposed grounded batteries connected with the collector rings, a second set of collector rings, a battery connected in series with the rings of the second set, wires for connecting any commutator ring or rings in the telephone circuit, means for connecting the collector rings with one set separately with certain commutator rings, means for connecting the other collector rings with the remaining commutator rings separately, and discharge rings connected with the said wires.

8. In a telephone system, a ringer having separate windings connected to ground at one end, wires connected with the opposite ends of the windings and including condensers, means for producing currents simultaneously through the windings for operating the ringers, and means for producing current through the windings separately.

In testimony whereof I affix my signature 95
in presence of two witnesses.
